UNITED STATES PATENT OFFICE.

WILLIAM H. KNOWLES, OF DETROIT, MICHIGAN.

INTERNAL-COMBUSTION ENGINE.

1,379,348.

Specification of Letters Patent. Patented May 24, 1921.

Application filed July 20, 1916. Serial No. 110,285.

To all whom it may concern:

Be it known that I, WILLIAM H. KNOWLES, a citizen of the United States of America, residing at Detroit, in the county of Wayne 5 and State of Michigan, have invented certain new and useful Improvements in Internal-Combustion Engines, of which the following is a specification, reference being had therein to the accompanying drawings.

10 The invention relates to internal combustion engines and has for its primary object increase in power and efficiency. To this end the invention comprises, first, the means for super-charging the cylinders with the 15 explosive gas, further, the means for completely eliminating or scavenging the explosion chambers of the burnt gases; further, the means for muffling the exhaust and at the same time reducing the back-pressure; 20 and further, various specific features as hereinafter set forth.

In the drawings:

Figure 1 is a longitudinal section through the engine, partly in elevation;

25 Fig. 2 is a cross-section thereof in the plane of one of the cylinders;

Fig. 3 is a cross-section in the plane of one 30 of the valves;

Fig. 4 is an enlarged section through the muffler;

Fig. 5 is a section on line $y-y$ of Fig. 3; and

Fig. 6 is a section on line $x-x$ of Fig. 3.

My improved construction preferably 35 comprises a plurality of power-cylinders cast *en bloc*, and preferably with one valve-cylinder serving to control two power-cylinders. Each power-cylinder contains a plurality of pistons arranged to produce a compression pump as well as the explosion 40 chamber, and the transfer of the gases compressed by the pump to the power-cylinder, as well as the admission and exhaust of the latter are controlled by the valves in the 45 valve-cylinder, the compression charges being temporarily stored within the valve. In detail, A and A' are the power cylinders, which are of sufficient length to receive two separated pistons B and B' connected by a rod C passing through an intermediate head or partition D. The cylinders A and A' are provided with water-jackets E and the heads D are preferably hollow and connected with said water-jackets for proper cooling. F is a crank 50

case and G the crank-shaft therein, which is connected by pitman rods H and H' to the lower pistons B'.

Each valve cylinder I is arranged intermediate a pair of power cylinders and is 60 preferably arranged with its axis at an angle to the axes of the power cylinders. Within each valve-cylinder are arranged preferably a pair of sleeve valves J and J', and within these sleeves is a hollow core member K 65 which is divided by partitions into the separate chambers L and L', L² and L³. There is also an exhaust conduit M arranged within the hollow core and preferably extending outward through the upper end thereof 70 and connecting with the exhaust manifold N. O is a fan casing arranged concentric with the crank-shaft at one end of the engine and containing a revolving fan P mounted on said crank-shaft. The suction port of the 75 fan is connected with the exhaust manifold N and the discharge is tangential.

The sleeve valves J and J' are provided with a plurality of ports for controlling the admission and exhaust of each of the pair 80 of power cylinders, also admission to and discharge from the pump of each cylinder, while the air and gases compressed by the pump are temporarily stored within the chambers L² and L' of the hollow core K. 85 Specifically, the ports are so arranged that air passes through the chamber L³ in the hollow core and is admitted through the port 1 to the chamber Q below the head D and between the same and the piston B', so 90 that in the down-stroke of said piston a volume of air will be drawn into the cylinder and in the up-stroke of said piston the air will be compressed and finally ejected through a port (not shown) into the chamber L² within the hollow core. In the same manner the ports are arranged to control 95 admission of gas or richly carbureted air into the chamber R above the partition D and between the same and the piston B, so that in the up-stroke of said piston a volume 100 of gas will be drawn in through the chamber L and port 2 and will be compressed upon the down-stroke and ejected through a port 6 into the chamber L' within the hollow 105 core. The valve sleeves J and J' further control the passage of the stored air and gas into the combustion chamber and the exhaust of the burnt gases from the explosion chamber. As shown, the stored air 110

passes through the port 3 and the stored gas passes through the port 4 into the combustion chamber, and the burnt gases pass from the explosion chamber to the exhaust manifold through the port 5. The various ports for performing these several functions are suitably located and distributed along the cylindrical valve shell, and leakage is prevented by arrangement of packing rings S 10 and S' surrounding the shell which divide the surface thereof into different zones.

In operation each reciprocation of the pistons within the cylinder will cause the pumping of a volume of air and a volume of 15 gas, each equivalent to the volume displaced by the piston in the explosion chamber, and these pumped volumes will be stored in the chambers L² and L' within the hollow core. At the completion of each power stroke of 20 the piston B the exhaust valve will open and slightly later the port 3 will be opened for admitting air stored in the chamber L² into the combustion chamber. The point of admission of the air is preferably located near 25 one end of the explosion chamber, while the exhaust is located near the opposite end, thereby permitting the incoming air to displace or scavenge the cylinder of burnt gases. After this scavenging operation the port 4 30 will be opened to admit the compressed gas into the explosion chamber, the pressure upon the gas in the storage chamber being sufficient for this purpose. All of the ports 35 communicating with the explosion chamber are then closed and the charge is compressed by the upstroke of the piston B, ignition taking place at the top of the stroke to develop power in the succeeding down-stroke. Thus there is an explosion in each cylinder for 40 each revolution of the crank-shaft, and as there is a super-charge of gas for each explosion a marked increase in power is obtained.

The power of the engine is further increased by reducing the back-pressure on the 45 exhaust, which is accomplished by the fan P. This fan performs the further function

of a muffler, as the continuous rotation of the blades will prevent concussion or recoil of the gases after each explosion.

By reason of the fact that there is an explosion for each revolution the valves may be operated directly from the crank-shaft, which avoids the usual complication of a cam-shaft and step-down gear connection 55 between the same and the crank-shaft. Thus the whole construction is simplified and the substitution of sliding sleeve valves for the usual puppet valves eliminates noise and insures large port areas.

What I claim as my invention is:

1. In an internal combustion engine, the combination with a plurality of power cylinders, of a valve cylinder, means within said power cylinders for compressing gases and means within said valve cylinder for transferring said compressed gases, said gases being temporarily stored within said valve cylinder, and for controlling the admission and exhaust of said cylinders.

2. In an internal combustion engine, an engine cylinder, a cylindrical member provided with separate chambers for respectively conducting air and gas to the engine cylinder and exhaust gases from said engine cylinder, and concentric valve sleeves surrounding said cylindrical member and controlling the passage of the air, gas and exhaust gases.

3. In an internal combustion engine, an engine cylinder, a valve cylinder provided with chambers for storing air and gas communicating with said engine cylinder at different points and also provided with a passageway for the exhaust gases communicating with said engine cylinder, and valve mechanism within said valve cylinder for controlling the passage of air and gas into and out of said chambers at different points therein and for controlling the passage of 85 the exhaust gases through said passageway.

In testimony whereof I affix my signature.

WILLIAM H. KNOWLES.
